NURSING BRASSIÈRE

Edward Keller, Forest Hills, N. Y.

Application August 27, 1948, Serial No. 46,451

2 Claims. (Cl. 128—280)

1

The invention relates to an undergarment, and more particularly to a nursing brassière embodying two bust supporting sections, to the interior surfaces of which are detachably applied two protective moisture repellent pads. The brassière constructed in accordance with my invention is further characterized by a front opening feature making it possible to readily open the brassière for the purpose of feeding an infant and to remove and replace one or both of the moisture repellent pads when necessity arises therefor, without requiring the removal of the entire brassière from the body.

My novel brassière is further characterized by a construction which imparts to the wearer complete breathing ease and relief from muscular tension or restriction while providing the necessary protection while nursing an infant, not otherwise capable of attainment with the conventional type of brassière. Further comfort to the wearer is provided by incorporating in my brassière an adjustable elastic back.

It is therefore the object of the present invention to provide a construction of nursing brassière which will support the busts in proper position for ease and comfort of the wearer during the extended period that nursing of an infant is necessary and to provide, as an adjunct to such brassière, removable sanitary, moisture repellent pads which may be readily attached to the interior of the breast sections and upon their becoming soiled, as by the seepage of milk from the breasts, replaced by clean pads. An important advantage of my novel nursing brassière is of course the fact that the protection afforded by the moisture repellent pads makes possible the appearance of the mother in public without danger of seepage of moisture through the brassière to the outer garments during this trying period.

Specific embodiments of my novel structure are illustrated in the accompanying drawing in which

Fig. 1 is a front view of the interior of the two portions of a brassière constructed in accordance with my invention and shown separated at the front and back;

Fig. 2 is a similar view of the interior of one of the bust sections illustrating the manner of detachable securing of the moisture repellent pad thereto;

Fig. 3 is a perspective view of one of the moisture repellent pads;

Fig. 4 is a perspective view of another embodiment of a brassière constructed according to my invention, as it is worn upon the body, illustrating

2

a modified form of front and rear fastening structures, by means of which the brassière is secured to the body, the entire brassière being shown in open position; and

Fig. 5 is a fragmentary view of the manner of detachable securing of the pad to a bust section.

Referring more particularly to the drawing, in which similar reference characters identify similar parts in the several views, each half of the brassière consists of a bust supporting section 6 terminating at one side in a body encircling strap or tape 7. Each bust section is connected to the body encircling strap 7 by a tape 8 with a similar tape 9 extending horizontally throughout the circular portion of the bust section and each bust section being conventionally provided with a dart 10 to shape the section. Throughout the lower portion of each bust section is a tape 11 between which and the fabric of the bust section are sewn fastener elements 12.

In the particular embodiment illustrated in Figs. 1 and 2, the righthand bust section is provided upon the inner side thereof with a tape 13 having sewn thereto a plurality of hooks 14 adapted to cooperate with corresponding eyes (not shown) secured within a tape along the adjacent side of the lefthand bust section, for effecting closure of the brassière about the body at the front, a strip 15 of napped material covering the tapes and hooks and eyes to protect the body therefrom.

The brassière of Fig. 1 has its body encircling bands 7 provided with conventional fastener structures at the rear, one fastener structure 16 being secured to one of the bands 7 and the other fastener structure 17 to the other of such bands through an elastic strap 18. The brassière is also provided with the conventional shoulder straps 19.

In Figs. 1 and 2 is shown one of the removable sanitary moisture repellent pads in position within a bust section. Such moisture repellent pad is shown in perspective in Fig. 3 and comprises a cup-shaped, substantially triangular strip of fabric 20 having its lower edge substantially straight, and provided throughout such lower edge upon the face to be applied to the interior of the bust section, with a tape 21 between which and the pad body are secured the cooperating snap fastener elements 22 by means of which the pad is to be detachably secured to the interior face of each bust section by engaging the snap fastener elements 22 of the pad with the snap fastener elements 12 of

the tape 11 of each bust section. The pad 20 upon the surface thereof which is to face the interior of each bust section, is lined with a water-repellant material 23 which may be of any sheet material such as is known on the market and comprises a translucent film made from chlorinated rubber or any equivalent moisture repellent sheeting.

In the utilization of the embodiment of my novel brassière shown in Figs. 1 and 2, the garment is donned by fastening the straps bearing the fastener structure 16 and 17 in the back and thereafter fastening the hooks and eyes in the front of the brassière, or the garment may be donned in the reverse order of engaging the fastening structures. In other words, the garment may be placed upon the body of the wearer in whatever manner is more convenient, namely by fastening the two component parts first in the back and then fastening the front thereof together, or vice versa.

However, when necessity arises for opening the brassière, for instance for the purpose of feeding an infant, the front opening fasteners may be disengaged, permitting the bust section to be flared away from the body so as to expose the breast to the child.

For the purpose of removing the water-repellant pad and replacing it with a clean one, the front opening will be found extremely convenient, as the pad may be readily removed by merely disengaging the fastener structures along the tape 11 and replacing the moisture repellent pad with a clean or new one by applying the new pad to the tape 11 by means of the snap fastener structures 12 and 22.

In the embodiment of my novel brassière illustrated in Fig. 4, substantially the same general structure of bust sections is utilized but the manner of securing of the brassière about the body of the wearer is of slightly different form. In such embodiment, the brassière is secured at the back by means of an elastic adjustable strap 24 which at each end may have a plurality of pairs of hooks and eyes 25 and 26, one pair of such hooks 25 being used upon the end of each body encircling band 27 but with two lines of eyes 26 at each end of the elastic strap 24, whereby a degree of adjustability may be secured by securing the hooks 25 to either pair of eyes 26.

The front opening of the brassière is also of somewhat different construction in that, instead of using the lines of hooks and eyes as in the first embodiment of my structure, the lefthand bust section 27a is provided with an elongated extension 28 which extends, when the garment is upon the body, substantially over the lower portion of the righthand bust section and is secured in position by means of elastic strap 29, carrying at its end a hook 30 which is adapted to engage

an eyelet 31 provided within a loop 32 extending from the line of juncture of the righthand bust section 33 and its body encircling strap (not shown).

In the second embodiment, the two bust sections are also joined at the front by means of cooperating hooks and eyes 34 and 35, so that the garment is secured about the body of the wearer even before the flap 28 is brought to its position beneath the righthand section and secured thereto by fastening the hook 30 in the eyelet 31 of the loop 32. By this construction, substantially the same effect and capacity of the wearer to open the bust sections and to replace the moisture repellent pads of each bust section is afforded as in the first embodiment.

I claim:

1. A brassière comprising a pair of breast receiving sections and a pair of body encircling bands integral therewith, means for securing the brassière about the body of the wearer at the rear, means for detachably securing together the breast receiving sections at the front of the brassière, a moisture repellent pad detachably secured within each breast receiving section, a tape secured by stitching along the bottom of each breast receiving section, a plurality of fastener elements secured within said tape, and a plurality of cooperating fastener elements along the bottom of each moisture repellent pad.

2. A brassière as claimed in claim 1 in which the means for detachably securing together the breast receiving sections at the front comprises an extension of one of the body encircling bands, a fastener structure at the end of the opposite body encircling band, a cooperating fastener structure at the inner end of the extension, a fastener at the free end of the extension, and a fastener positioned approximately at the midpoint of the second body encircling band, whereby the two sets of fastener structures, when closed, effect a complete closure of the brassière about the body of the wearer with the extension of one of the body encircling bands disposed along the bottom of the second breast receiving section.

EDWARD KELLER.
